UNITED STATES PATENT OFFICE.

ALFRED B. HUTCHINSON, OF BROOKLYN, NEW YORK, ASSIGNOR TO THE
GLEN COVE MACHINE COMPANY, (LIMITED,) OF SAME PLACE.

WOOD-PLANING MACHINE.

SPECIFICATION forming part of Letters Patent No. 404,088, dated May 28, 1889.

Application filed August 13, 1887. Serial No. 246,829. (No model.)

To all whom it may concern:

Be it known that I, ALFRED B. HUTCHINSON, of Brooklyn, (Green Point,) in the county of Kings and State of New York, have invented a new and useful Improvement in Wood-Planing Machines, of which the following is a specification.

My invention in its entirety relates to wood-planing machines which comprise both an upper and under or lower cutter-head and side cutter-heads; but the several features of the invention may be embodied in machines which do not comprise all these cutter-heads.

I will describe in detail a planing-machine embodying my improvement.

In the accompanying drawings, Figure 1 is a side elevation of such parts of a wood-planing machine as are necessary to illustrate my invention. Fig. 2 is a longitudinal section, 20 and Fig. 3 a plan of the machine. Figs. 4 and 5 are respectively transverse sections upon about the planes indicated by the dotted lines $x x$ and $y y$, Fig. 3. Fig. 6 is a vertical section showing in detail a certain presser-bar holder, a presser-bar and chip-breaker, together with their supports, employed in the machine.

Similar letters of reference designate corresponding parts in all the figures.

30 A designates the side frames of the machine, in which the several working parts are journaled or otherwise supported, as I shall now describe.

B designates the upper cutter-head.

35 C designates the side cutter-heads, and D designates the lower cutter-head, as best shown in Figs. 1 and 2.

E E' designate, respectively, upper and lower feeding-rolls, of which three pairs are 40 here represented, and which are severally operated in the same way, the same letters of reference applying to each pair of feed-rolls and to the several parts which are employed in connection therewith. The several cutter-heads are provided with journals, or have spindles which are supported in suitable boxes and are driven by belting in the usual way. The side cutter-heads, C, are upon side cutter-head spindles, C', which are journaled 45 in the side cutter-head frames, C², and these frames C² are supported mainly by a bar, C³,

here represented as round and extending transversely across the machine, the ends of said bar being supported in boxes C⁴. The lower portions of the frames C² are steadied 55 by a bar, C⁵, and the frames C² may, one or both of them, be adjusted laterally upon the bar C³ by the means usually employed. The lower feed-rolls, E', may be fitted in stationary boxes, while the upper rolls are journaled, as is usual, upon boxes e, which are adjustable upward and downward upon roller-stands E² in the well-known manner.

F designates what is usually termed the "pinion-shaft" of the machine, and which 65 has a pinion, f, engaging a gear-wheel, F', which serves to impart motion to two wheels, F², which are respectively upon the journals of two of the lower feed-rolls, E', and f' designates an intermediate or transmitting pinion, which serves to transmit motion from one to another of two wheels, F², thereby providing for the positive driving of the three lower feed-rolls here represented. Each lower roll, E', is connected by lower and upper expansion-gears, e' e², in a well-known manner with a gear-wheel or pinion upon the upper roll, E, and in this way the upper roll is driven, notwithstanding its adjustment up and down upon the roll-stand E². 75

I have in the drawings represented the gear-wheels and pinions in whole or in part by dotted circles, as it is deemed unnecessary to show all their teeth.

The upper roll-boxes, e, which are on opposite sides of the machine, are connected directly and in a well-understood manner by rods e³ with arms e⁴, which are upon a rock-shaft, E³, and which insures the upper roll-boxes upon opposite sides of the machine 90 rising and falling simultaneously.

I will now proceed to a more detailed description of parts to which the most of my novel features relate. The lower cutter-head, D, which is at the delivery end of 95 the machine, is supported in a cutter-head frame, D', as is usual, and on the front side thereof, or on the side on which the lumber enters, is a bar or mouth-piece, D², while on the rear side thereof, or on the side on which 100 the lumber is delivered, is a bar or mouth-piece, D³. The bar or mouth-piece D³ has in

it slots d , which receive screws d' , securing the bar or mouth-piece to a bar-holder, D^4 , which extends across the machine and is supported by projections d^2 at its ends, which fit in pockets d^3 in a yoke or cross-bar, D^5 , extending across the machine. This yoke or cross-bar D^5 is constructed with downwardly-extending arms D^6 , which are pivoted at d^4 , below the cutter-head frame D' , to the main side frames of the machine. The slots and bolts d d' provide for adjusting the bar or mouth-piece D^3 laterally toward and from the lower cutter-head, D , in a well-understood manner.

15 The bar-holder D^4 may be vertically adjusted relatively to the cross-bar or yoke D^5 by adjusting-screws d^5 , which are inserted through the ears or projections d^2 upon the bar-holder D^4 , as is best shown in Fig. 4, and 20 which pass freely through holes in the bottoms of the pockets and bear upon shoes or cam-like surfaces d^6 upon the cutter-head frame D' of the machine, as best shown in Fig. 2, and also in Fig. 4. It will be understood that if the bar-holder D^4 has been by 25 the screws raised away from the bottoms of the pockets d^3 the bar-holder will fall slightly in the pockets as the cross-bar or yoke D^5 is swung downward and away from the lower cutter-head, D , as shown by the direction of the arrow in Fig. 2; but as these parts are returned or swung upward and toward the cutter-head the lower ends of the screws d^5 will come to a bearing upon the projections or cam-like 30 surfaces d^6 , and will raise the bar-holder D^4 to its normal position in the pockets. The bar-holder D^4 may be kept from dropping out of the pockets, when it is swung downward, by a pin, d^7 , inserted laterally in the pocket 35 and engaging an upright shouldered groove, d^8 , in the end of the bar-holder D^4 , as best shown in Fig. 4, or by any other suitable means.

When the yoke or cross-bar D^5 is swung upward to the position represented in Fig. 2, it 45 may be held in that position and also drawn toward the cutter-head by means of horizontally-swinging yokes or clamps D^7 , (shown in Fig. 3,) which are provided with clamping-screws d^9 . I have also shown as secured to the cross-bar D^5 and its arms D^6 by bolts d^{10} , as shown in Fig. 2, an extension-table, D^8 , which is formed separate from the bar or mouth-piece D^3 . Above the lower cutter-head, 50 D , is arranged a presser-bar, J . This presser-bar is supported near its ends by means of screws j , journaled in upwardly-extending brackets j' , which are hinged to the frame at j^3 . Upon the upper ends of the screws j are bevel gear-wheels j^3 , which mesh with other bevel gear-wheels j^4 , mounted upon a horizontally-extending shaft, j^5 . The shaft j^5 has squared ends, which may be rotated to cause the raising and lowering of the presser J , as desired. 55 Ordinarily the boxes C^4 , which support the ends of the bar C^3 , are secured to the main side frames, A ; but according to my invention I have represented them as secured by bolts c to the upright wall of the upper cutter-head bed B' , as is best shown in Fig. 1, and 75 accessible at the side of the machine. The bolts c pass through slots c' in the cutter-head bed B' , as is shown by dotted lines in Fig. 1, but are accessible at the side of the machine, and after loosening them the boxes C^4 may be 75 adjusted upward and downward by adjusting-screws c^2 between the boxes and the main frame, and which are also accessible at the side of the machine.

The upper cutter-head, B , is supported in 80 boxes B^2 , which are adjustable upward and downward along slides B^3 , in the usual way, and which have brackets b , to which is secured a holder, B^4 , for a presser-bar and chip-breaker, B^5 . As best shown in Figs. 1 and 3, 85 the presser-bar holder B^4 extends across the top of the brackets b and is secured to them by screws b' , passing through slots b^2 , as best shown in Fig. 3. Thus the adjustment of the holder B^4 and the bar B^5 toward and from the 90 upper cutter-head, B , is provided for. The ends of the bar and chip-breaker B^5 pass beneath the brackets b , and the bar and chip-breaker are secured to the holder by bolts b^3 , as best shown in Fig. 3. Both the holder B^4 95 and the bar and chip-breaker B^5 extend outward laterally beyond the brackets b sufficiently to receive an adjusting-screw, b^4 , which is journaled so as to prevent its lengthwise movement in the end of the holder B^4 , and is 100 threaded to engage the end of the bar B^5 , as best shown in Fig. 1. Consequently when the screws b^3 are loosened (their holes being slotted) the screws b^4 may be readily reached at 105 the side of the machine without extending the arm over the moving parts and into out-of-the-way places, and without inconvenience or danger the bar or holder may be raised or lowered relatively to the work.

I have represented the shafts of the expansion-gears e' e^2 as supported by a bracket, E^4 , which comprises upper and lower hubs, e^5 , connected by parallel arms e^6 , so as to give it lightness. The shaft of the lower gear, e' , is journaled in the lower hub e^5 and the shaft 115 of the upper gear in the upper hub e^5 , while below the lower hub the bracket extends inward toward the lower roll, and, as here shown, slightly downward, the end being pivoted at e^7 in the roll-stand E^2 . The upper end of the bracket E^4 is supported by a swinging link, E^5 , which is pivoted concentric with the journal of the upper roll, E , it being here shown as pivoted upon the upper roll-boxes, e .

The letters of reference which are applied 125 to the expansion-gears and their appurtenances apply equally to each pair of feed-rolls, the construction being the same. One construction heretofore employed has been to form the bearing for the shaft of the lower 130 expansion-gear, e' , directly in the roll-stand E^2 , and consequently the shaft has had to be removed endwise before the expansion-gears could be removed. It will be seen here, how-

ever, that by simply withdrawing the pivot e^7 and then slipping the eye of the link E^5 off from the upper hub of the bracket E^4 the bracket and its two expansion-gears may be easily withdrawn and removed. I have here shown each pair of feed-rolls as provided with an adjusting-screw, G , having at the top an operating-handle, g , and journaled at g' in the top of the roll-stand E^2 in such manner as to provide for its lengthwise movement upward, or in one direction, as best shown in Fig. 5. As here shown, the threaded portion of this screw directly engages the upper roll-box, e , as best shown in Fig. 5, and to this screw are applied the weighting-connections for holding down the upper roll with a yielding force. In the case of the two pair of feed-rolls, which are at the feeding end, or the right-hand end of the machine in the drawings, I have shown two screws G as connected by a cross-bar or yoke, G' , and a link or rod, G^2 , with a weighted lever, G^3 ; but in the case of the last pair of feed-rolls, which is adjacent to the lower cutter-head, D , and near the delivery or left-hand end of the machine, I have shown the screw G as connected by a hanger, G^4 , with the weighted lever G^3 . It will therefore be seen that through the screws G the weighting-connections apply their force to the upper roll-boxes, e , and their roll, and when the lumber passes into the machine the screws are free to rise with the roll and roll-boxes as the weighting connections are overcome. By shifting the screws G the upper roll-boxes may be raised or lowered to a definite degree. It will be seen that the adjusting-screws G , being arranged in the roll-stands E^2 , and not on the outside thereof, are out of the way, while they are readily accessible from the side of the machine, and by engaging the screws directly with the upper roll-boxes other connections which have heretofore been employed are dispensed with.

What I claim as my invention, and desire to secure by Letters Patent, is—

1. The combination, with the main frame, of the cutter-head frame therein having the shoes or cams d^6 , the cross-bar or yoke D^5 , having downwardly-extending arms pivoted to the main frame, and having the pockets d^3 , the holder D^4 for the bar or mouth-piece, having its ends fitting said pockets and provided with adjusting-screws extending through the bottoms of the pockets and resting on said shoes or cams, and the bar or mouth-piece D^3 , supported on the said holder and laterally adjustable thereon, substantially as herein described.

2. The combination, with a main frame, of an upper cutter-head bed, B' , a bar, C^3 , side cutter-head frames supported upon said bar, boxes C^4 , in which said bar is supported near its ends, which boxes are bolted to the cut-

ter-head bed B' , and adjusting-screws c^2 between the main frame and said boxes for vertically adjusting the said boxes, substantially as specified.

3. The combination, with the upper cutter-head boxes and brackets or projections thereon, of a presser-bar holder secured upon said brackets so as to be laterally adjustable and extending beyond said brackets, a presser-bar and chip-breaker secured to said holder and having projections which extend outward under the brackets, and adjusting-screws between the projecting ends of the holder and the bar and chip-breaker, and arranged on the outer sides of the brackets, substantially as herein described.

4. The combination, with the lower cutter-head and its bar or mouth-piece adjustable toward and from the cutter-head and also adjustable vertically, of a yoke or cross-bar having downwardly-extending arms which are pivoted to the main frame below the cutter-head and on which the bar or mouth-piece is supported and adjustable, and an extension-table separate from the bar or mouth-piece and secured to the yoke or cross-bar and its arms, substantially as herein described.

5. The combination, with the feed-rolls and the expansion-gears whereby they are connected, and the roll-stand, of a bracket, E^4 , having a pivotal connection with the roll-stand and carrying the bearing for both the upper and lower gear-shafts or gears, and a swinging link, E^5 , pivoted concentric with the upper roll and connected with the top of said bracket, substantially as specified.

6. The combination, with the feed-rolls, the expansion-gears whereby they are connected, and the roll-stand, of the bracket E^4 , forming the bearing for both the upper and lower gear-shafts or gears, and having its end portion below the bearing extending inward toward the rolls and pivoted to the stand, and the swinging link E^5 , pivoted concentrically with the upper roll and supporting the upper end of the bracket, substantially as herein described.

7. The combination, with an upper presser-roll, of a roll-stand, an upper roll-box sliding on said roll-stand, a weight, connections between the said weight and the roll-box whereby motion is transmitted from one to the other, and an adjusting-screw journaled in the roll-stand and shouldered to prevent its lengthwise movement in one direction, said screw being directly engaged with the roll-box, whereby the roll-box and the weight may both be operated by the screw at one operation, substantially as specified.

ALFRED B. HUTCHINSON.
